RONALD E. BOOTH, OF SEATTLE, WASHINGTON.

WHEELBARROW.

1,242,418.

Specification of Letters Patent.

Patented Oct. 9, 1917.

Application filed May 24, 1916. Serial No. 99,646.

To all whom it may concern:

Be it known that I, RONALD E. BOOTH, a citizen of Great Britain, and a resident of Seattle, in the county of King and State of Washington, have invented certain new and useful Improvements in Wheelbarrows.

This invention relates to wheel barrows, and has for its principal object to provide an improved and novel form of knock-down wheel barrow, the individual members of which are foldable with respect to one another, so as to form when in a folded position a compact, flat and easily carried package. Another object is to provide an improved form of extension handle construction. While my wheel barrow is adaptable for almost any purposes to which a wheel barrow is adaptable, yet I have in mind more particularly the lighter or toy wheel barrows which children use at the beaches and summer resorts. In this connection it is advantageous to have a wheel barrow which is foldable, takes but very little room, and is easily carried, which may be taken upon railway coaches, automobiles, buggies and the like when traveling.

In the drawings Figure 1 is a top plan view of my device shown in a folded position. Fig. 2 is a similar side elevation. Fig. 3 is a bottom elevation of same. Fig. 4 is a side elevation of my wheel barrow shown in position for use. Fig. 5 is an enlarged detail view of my improved extension handle device. Fig. 6 is a similar view of the same shown in a folded position. Referring more particularly to the drawings numeral 1 indicates side members which are tied together by strut members 2. A main bottom member 3 is secured to the side members 1 and strut members 2. A front end gate 4, and a rear end gate 5 are hinged to floor member 3. The end gate members are adapted to fold down upon the body member 3, and to lie flat thereon, when the wheel barrow is folded or knocked down. Side boards 6 are removably attachable to the frame members 1 and to the end gate members 4, and 5 by means of dowels and small hooks 7. When in the knocked-down position side boards 6 lie flat upon the top of the folded end gates, as clearly shown in Figs. 1 and 2, and are secured in said position by means of hooks 8 at the front, and 9 at the rear. An axle 10 is secured to members 1 by means of clips 11, which are turnable upon a pivot,

so that the axle is easily releasable from engagement with members 1. Axle 10 is threaded as at 13 near its central portion, so as to receive the wheel 13^a which screws upon the said axle, and which may be removed by simply unscrewing it from the said axle. When in the knocked-down or packed position, the wheel 13^a is retained by a peg 14, and hook 15 upon the underside of floor-board 3. Legs 16 are pivoted to the members 1, one on either side of the wheel barrow. In a folded position the legs 16 are parallel and adjacent to the members 1. When the wheel barrow is in use the legs 16 are swung at approximately right angles to the members 1 and the lower ends of said legs rest upon the ground while the upper ends extend along the outside of side-boards 6, to which they are secured by means of clips 17, which engage lugs 18. Handle 19 is secured to one of the legs 16, and is used for convenience in carrying the wheelbarrow when in the knock-down form. When it is not desired to use side-boards 6 in connection with the wheel barrow, the front end gate 4 is secured in position by means of straps 20, the one end of each of which is secured to the member 1, and the other end of which is adapted to engage the hook 7. Extension handles 21 are hinged to the rear end of members 1, and are foldable therewith, as shown in Figs. 1, 2 and 3. When in the extended position each of handles 21 is held against collapsing by means of a strap yoke 22, which is pivoted to the extension handle 21 at the end and a loop portion of which engages a notch 23 in the member 1. When in the folded position the yoke 22 swings up and over member 21, thereby holding the member 21 and 1 in a close or folded position with respect to each other. This is clearly shown in Fig. 6. When the side boards are not used in connection with the wheel barrow the legs 16 are left in the folded position, that is parallel and adjacent to the members 1. Auxiliary legs 24 are pivoted on the inner side of members 1, and fold in against the under side of bottom member 3, and adjacent to the inner side of the side members 1. The legs 24 may be extended and used to rest the wheel barrow on when the side boards are not in use in connection with the wheel barrow. While applicant is aware that wheel barrows of many forms have

heretofore been used and patented, yet he believes that wheel barrows of the form shown and in which the novel idea of making them knocked-down, and the particular 5 method of assembling to be new.

While I have shown a particular form of embodiment of my invention, I am aware that many minor changes therein will readily suggest themselves to others skilled 10 in the art without departing from the spirit and scope of the invention, and I therefore desire to avoid being limited to the exact claims.

Having described my invention, what I 15 claim as new and desire to protect by Letters Patent, is—

1. In a collapsible wheel barrow including a flat body frame and a wheel removably secured onto a wheel shaft, the combination 20 of extensible hinged handles and means for locking said extension handles in an open or closing position, said means including a yoke pivoted to the extension portion of said handle and adapted to engage a

notch in the top of the permanent portion 25 of said handle when in an open position.

2. In a collapsible wheel barrow which includes a rigid body frame, a combination of a centrally threaded wheel shaft removably mounted on said frame, a threaded 30 wheel removably secured on to said shaft, legs centrally pivoted to said frame and normally extending above and below said frame, whereby the upper portion forms a support for the sideboards, auxiliary legs 35 which are foldable beneath said body, extensible handles hinged to said body and foldable beneath said body, and means for locking said handles in an open or closed position, said means including yokes pivoted 40 to the said handles and adapted to engage notches in the said frame when the said handles are in an extended position, and which are adapted to engage the top of the frame when the handles are in a folded 45 position.

RONALD E. BOOTH.
